Mr. St. John,
Dear Sir, I am
Yours truly
John W. Forney.

Patented Aug. 21, 1928.

UNITED STATES PATENT OFFICE.

SIGMUND JOSEPH PENTLER AND OTTO R. SHORT, OF WAUSAU, WISCONSIN.

STITCH-DOWN SHOE AND METHOD OF MAKING THE SAME.

Application filed October 30, 1923. Serial No. 671,700.

This invention relates to stitch-down shoes and is an improvement over that described in our prior Patent Number 1,320,797 for stitch-down shoes issued November 4, 1919, 5 and has in general the same objects as those enumerated in such patent.

Further objects are to provide a stitch-down shoe in which a cheaper insole may be used, to provide a stitch-down shoe in which 10 no strain is imposed on the insole by the upper leather, in which a lighter and less expensive thread may be employed for securing the lining to the insole than that necessary for shoes employing Goodyear 15 welts or those of the construction illustrated in our above noted patent, and to provide a shoe which requires less skilled workmen for its production than stitch-down shoes as formerly constructed.

20 Further objects are to provide a stitch-down shoe which will retain its shape, which will wear longer, in which the inner sole constitutes an active part of the shoe and is not merely cemented in place, and in which 25 there is no possibility of loosening of the inner sole or lining either from long wear or from being moistened.

An embodiment of the invention is shown 30 in the accompanying drawings, in which:— Figure 1 is a bottom view of a stitch-down shoe with parts broken away to illustrate the interior construction.

Figure 2 is an enlarged fragmentary section on the line 2—2 of Figure 1. 35 The shoe comprises an upper 1 and a lining 2, therefor. This lining is secured by means of blind stitching 3 or staples or other means to the inner sole 4,—the upper being free from such inner sole. It is to be noted 40 that the lining 2 is stitched to a channel or beveled portion of the inner sole 4 and that this channel portion provides a space for the inner ends of the lining and does not necessitate the passing of the lining between the doubler 5 and the inner sole 4. Consequently a 45 cork or other filling is not needed in this shoe as the inner sole directly contacts with the doubler 5 throughout the extent of such inner sole. Thereafter, a doubler 5 is positioned, as shown in Figures 1 and 2, and the 50 upper has its marginal edge 6 turned outwardly and positioned on top of the doubler 5. Thereafter, a line of stitching 7 is run around the shoe and permanently connects the upper 1 with the doubler 5. When the 55 shoe is thus far completed, the outer sole

8 is positioned beneath the doubler 5 and a welt strip 9 is positioned above the outturned portion 6 of the upper, and a line of stitching 10 is run completely around the shoe 60 and through the welt strip, the outturned portion 6 of the upper, the doubler 5, and the outer sole 8, thus firmly securing the parts together.

It is to be particularly noted that it is 65 not necessary to glue the lining 2 to the inner sole 4, but that such lining is securely fastened thereto by means of stitching or stapling 3. It is to be noted further that less skill is required to stitch the lining in 70 place than is required where it is necessary to simultaneously draw down the upper 1 and stitch it also to the inner sole as has previously been the case. In addition to this a light thread may be used for the stitching 3 75 as well as a cheaper insole for the reason that these parts are not called upon to carry as much of a strain as has heretofore been the case.

It is further to be noted that the insole 80 forms an active part of the shoe and is not merely a lining which is inserted in the shoe and cemented in place but constitutes one of the portions of such shoe which aids in maintaining the shape of the shoe. Further, this insole will not become loosened and turn up when the shoe is wet as has heretofore been the case. It is further to be noted that the lining is stitched in place or 85 stapled in place and will not loosen or pull up from extended use or from becoming moistened. It will be seen, therefore, that the lining is maintained by this construction in a smooth and unwrinkled condition and is securely attached at all times. It is also 90 to be noted that the stitching or stapling of the lining does not have to be as accurately done as heretofore for the reason that this securing means is fully covered by the upper 95 and is not visible in the completed shoe.

100 It will be seen, therefore, that an extremely serviceable and more economical stitch-down shoe has been provided than has heretofore been possible, and that such shoe will retain its shape under the most adverse conditions.

105 In cases where it is not desirable to employ the doubler 5, as shown in the drawings, such doubler may be omitted and the outturned portion 6 of the upper is then positioned directly upon the outer sole 8. The welt strip 9 is then correctly positioned and suit-

able stitching is passed through the welt strip the outturned portion and the outer sole 8. Obviously, any desired order of stitching may be employed for securing these parts together; for example, the outturned portion 6 may be first stitched to the outer sole 8 and, thereafter, a line of stitching could be run through the welt strip, the outturned portion and the outer sole.

10 Although the invention has been described in considerable detail, it is to be understood that the invention may be variously embodied and is, therefore, to be limited only as claimed.

15 We claim:

1. In a stitch-down shoe, the combination of an upper and a lining, an inner sole having a beveled lower marginal edge, said lining having its marginal portion positioned 20 against this beveled edge, securing means joining said lining and said inner sole, said securing means extending only through said lining and said inner sole, said upper being turned outwardly at its marginal portions, 25 a doubler positioned in contact with the inner sole throughout the extent of the inner sole, securing means joining the outturned portion of said upper and said doubler, an outer sole positioned below said doubler, a welt strip positioned above said outturned portion, and a line of stitching passing through said welt strip, said outturned portion, said doubler and said outer sole.

2. In the manufacture of boots and shoes,

a method that comprises positioning a lining 35 against the edge face of an insole and sewing the lining to the edge to produce an inner shoe, positioning the insole in face-to-face contact with an intermediate sole so that the margin of the intermediate sole extends beyond the said edge face, positioning an upper about the lining with a marginal portion of the upper in contact with the margin of the intermediate sole, sewing the marginal portion of the upper to the said margin of 45 the second sole separately from the inner shoe to produce an outer shoe, whereby the inner shoe becomes positioned in the outer shoe, positioning the intermediate sole in face-to-face contact with an outer sole, and 50 sewing the outer and intermediate soles, the said margin of the upper and a welt together.

3. A boot or shoe having, in combination, an outer shoe, and an inner shoe positioned in the outer shoe, the inner shoe comprising 55 an insole and a lining sewed to the edge face of the insole, the outer shoe comprising an intermediate sole having a margin extending beyond the said edge and an upper and a welt sewed to the said margin, and an outsole positioned against the intermediate sole, the outsole being sewed to the intermediate sole and the margin of the upper.

In testimony that we claim the foregoing we have hereunto set our hands at Milwaukee, Wisconsin.

SIGMUND JOSEPH PENTLER.
OTTO R. SHORT.
